PROCESS OF REFINING PETROLEUM
DISTILLATE

Ernest S. Brown, Inglewood, and Donald B. Nutt,
El Segundo, Calif., assignors to Standard Oil
Company of California, San Francisco, Calif.,
a corporation of Delaware

Application July 9, 1932, Serial No. 621,578

19 Claims. (Cl. 196—32)

This invention relates to a process of treating petroleum distillates and particularly distillates containing mercaptans, for the purpose of sweetening them. The invention is particularly directed toward a process of sweetening petroleum distillates by means of a novel reagent, whereby mercaptans are readily converted into other unobjectionable compounds and the distillates otherwise improved in a rapid and economical manner, 10 without the use of extraneous air or oxygen.

The invention is also directed to a method of treating petroleum distillates and maintaining the treating agent in the most effective condition.

One of the customary methods of treating petroleum distillates involves the use of what is known as the "doctor solution". Doctor solution is ordinarily prepared by dissolving litharge in a caustic soda solution, sodium plumbite being thus formed. Free sulfur is generally used in addition. The doctor solution appears to sweeten petroleum distillates by converting certain types of sulfur bodies to other compounds which are sweet to the doctor test and do not have an objectionable odor. There are numerous disadvantages to the use of doctor solution, however. For example, one of the disadvantages of the conventional doctor treatment is that when treating petroleum distillates of relatively unstable color (such as cracked distillates), the doctor solution can not be reused without sacrificing the color of the distillate being treated. For this reason, it is difficult, if not impossible, to adapt the doctor treatment to a continuous operation and the chemical consumption is great, adding materially to the cost. Furthermore, as one of the steps of the doctor treatment is the addition of sulfur, the treating process is difficultly controlled in that it is substantially impossible to add only the precise and exact amount of sulfur required. Moreover, there is an appreciable loss of stock through the discarding or attempted revivification of the spent doctor solution.

The invention not only distinguishes from and obviates the prior difficulties encountered in the sweetening of petroleum distillates with doctor solution, but also obviates all of the difficulties hitherto encountered when attempts were made to use suspensions of lead sulfide in caustic. It is known that a suspension of lead sulfide in caustic is capable of sweetening certain distillates and such suspensions have been used heretofore while being subjected to the action of air brought into intimate contact with the oil and treating solution. Such treatment, however, could only be applied to certain distillates and during such

treatment, appreciable concentrations of dissolved lead compounds and soluble sulfides formed in the treating solution, rendering the same ineffective and moreover making it impossible to reuse the treating solution on cracked distillates. The presence of dissolved lead in the treating solution has a marked deteriorating effect upon the color of the treated distillate and although such soluble lead compounds are formed under all conditions, the use of air during the treatment merely aggravates the condition and renders this treating process commercially impractical.

As stated before, one of the disadvantages of the conventional doctor treatment is that, when treating petroleum distillates of relatively unstable color (particularly cracked distillates), the doctor solution can not be reused without sacrificing the color of the distillate being treated, unless practically complete removal of lead sulfide is accomplished before reuse. A suspension of lead sulfide is also likely to cause color reversion unless the treating process is controlled in accordance with this invention.

It has been found, however, that a suspension of lead sulfide in an alkaline medium can be satisfactorily and economically employed in the treatment of all distillates, including cracked distillates, either with or without the use of extraneous air or oxygen provided, however, that the treatment be carried out in accordance with the controlled conditions forming the subject matter of this invention. Moreover, by conducting the treating process in accordance with this invention, the treating agent or treating solution may be reused successfully for prolonged periods of time and therefore large quantities of distillate treated thereby with exceptionally good results.

More specifically, it has been found that the addition of carefully controlled amounts of either soluble lead compounds or soluble sulfides to the caustic suspension of lead sulfide (used as a treating agent) and the use of either no air or a minimum quantity of air, will eliminate all of the difficulties commonly experienced in lead sulfide treatment and result in a process which has marked advantages over either the common doctor treatment or the previously attempted treatments with lead sulfide suspensions.

An object of this invention, therefore, is to disclose and provide a method of controlling the treating step in such manner as to permit continuous reuse of the reagent without causing color reversion in the distillate being processed and without impairing the effectiveness of the reagent. Such control and the results attainable

thereby has not been practiced nor obtained heretofore.

It is an object of this invention to disclose and provide a method of treating petroleum distillates for the purpose of producing distillates which do not react to the doctor test, that is, which do not contain mercaptans.

An object of this invention is to disclose and provide a method of controlling the treatment of petroleum distillates with a reagent consisting of an alkaline suspension of lead sulfide, whereby said reagent may be used in a continuous manner even on distillates of relatively unstable color, without sacrificing the color of the distillate being treated.

Another object of this invention is to disclose and provide a process of treating petroleum distillates by means of a reagent substantially free from soluble lead salts or compounds.

Another object is to disclose and provide a continuous process of treating petroleum distillates to produce doctor negative distillates without deterioration in regard to color.

Another object is to disclose and provide a method of sweetening petroleum distillates by means of a specific reagent and to disclose a method of maintaining said reagent in an effective condition during continuous use thereof.

A still further object of the invention is to disclose and provide a method of treating distillates for the purpose of producing doctor negative distillates without the use of extraneous air or oxygen.

An object of the invention is to disclose and provide a novel treating agent for use in sweetening petroleum distillates.

Another object is to disclose and provide a novel treating agent capable of being continuously employed in the sweetening of petroleum distillates.

A still further object is to disclose and provide a method of operation whereby a treating agent may be continuously revivified during continued use in the sweetening of distillates.

These and other objects, uses and advantages of the invention will become apparent to those skilled in the art from the following detailed discussion of the conditions, steps and elements embraced by the process of this invention.

In order to facilitate understanding of the invention, reference will be had to the appended drawing, in which

Fig. 1 diagrammatically represents one arrangement of elements whereby the process may be placed into operation.

Fig. 2 diagrammatically represents a modified arrangement of elements whereby the sweetening of petroleum distillates may be carried out continuously in accordance with this invention.

As has been stated hereinbefore, the invention is particularly directed towards a process which employs an aqueous alkaline solution containing lead sulfide in suspension as a treating agent. This treating agent or reagent should be essentially free from soluble lead salts or compounds and/or soluble sulfides, and the process of this invention includes steps and means for maintaining the reagent substantially free from these interfering components.

A suitable reagent for use in this process may be prepared from any caustic soda or potash solution having a gravity of between about 1° Bé. and the strongest solution available, although solutions of between 8° Bé. and 30° Bé. are generally to be employed. Preferably, a caustic soda solution of between about 20° and 30° Bé. is employed.

Reagents prepared with caustic soda solutions weaker than about 12° Bé. are relatively slow in effecting the sweetening reaction, while those prepared with solutions above about 30° Bé. have a tendency to cause emulsification with some petroleum oils undergoing treatment, particularly when severe agitation is employed. In order to maintain the reagent in most effective condition for rapid refining operations, it is found desirable to withdraw the solution or reagent when it has been diluted to a point materially below 20° Bé. and to replace it with a fresh 30° Bé. solution.

The reagent may contain in suspension from between about 0.1 and 2.0 lbs. and preferably between 0.5 and 1.0 pounds of lead sulfide per gallon of reagent; a reagent containing about 0.75 pounds of lead sulfide per gallon has been found to give excellent results. The range of concentration may be materially varied, however, without rendering the process inoperative. Lead sulfide may be prepared by precipitation from lead acetate or other soluble lead salt with a solution of sodium or other soluble sulfide in carefully regulated amounts. As a matter of fact, a suitable reagent or treating solution may be prepared by adding sodium sulfide to an ordinary doctor solution, the sodium sulfide being added in quantity sufficient to precipitate the lead in the form of lead sulfide. Care should be taken, however, that the reagent is substantially free from any soluble lead compounds or from an excess of soluble sulfides. In actual practice, it has been found that the sweetening reaction of a fresh reagent mixture is very greatly improved after some, at least, of the lead sulfide has become oil-wetted. For this reason, it has been found desirable in preparing a reagent for use, to recirculate the reagent after the precipitation of lead sulfide therein in contact with an oil or distillate, such as a previously purified distillate in a closed system until the sulfide becomes oil-wetted, in part at least.

The process of treating petroleum distillates consists of the steps of contacting the sour distillate with the treating solution or reagent in any suitable manner, contact being maintained for an appropriate period of time. As the time of contact required is influenced by the character, gravity and source of the petroleum distillate and the alkalinity and lead sulfide content of the reagent, it is impossible to state any definite contact times.

It is to be understood that the process is applicable to a wide variety of petroleum oils and distillates. Primarily, the process is applicable to petroleum distillates of the kerosene and gasoline type but any sour distillate may be treated by the process and by the reagent described hereinabove, irrespective of the sulfur content of the distillate. The process and reagent are particularly adapted for the treatment of cracked gasolines and kerosenes. In all instances, however, the reagent or treating solution must be maintained substantially free from lead compounds and soluble sulfides.

The mercaptan sulfur content of the distillate being treated may necessitate a slight modification in the manner of carrying out the process. It has been found, for example, that petroleum distillates containing 0.02%–0.03% or less of mercaptan sulfur may be treated without the use of extraneous air or oxygen during agitation or contacting of the distillate with the treating solution. Distillates containing larger quantities of mercaptan sulfur generally require the introduction of extraneous air or oxygen during the contacting

step, but only a very small amount of air or oxygen is required. For example, cracked gasoline distillates containing 0.1 to 0.12% of mercaptan sulfur should be treated with not more than about 5 0.02-0.03 cubic feet of air per gallon of oil. The amount of air or oxygen introduced during the treating step should be carefully controlled since any excess of air over that required to effect the sweetening reaction develops the soluble plumbite 10 ion in the reagent and the presence of plumbite or of soluble lead compounds in general has been found to have a marked deteriorating effect upon the color of the treated distillate. In no case should there be present in the reagent more than 15 traces of soluble lead compounds for, as has been stated hereinabove, the presence of soluble lead compounds decreases not only the rate of sweetening but also causes a drop in the color of the treated oil. For this reason, it has been found 20 desirable to test the reagent being used at frequent intervals and to remove soluble lead or soluble sulfides by the addition of suitable chemicals.

One arrangement of elements in which the process may be effectively placed in operation is illustrated in Fig. 1. The naphtha or petroleum distillate to be treated may be admitted to the system by a line 1 provided with a valve 2, the line leading to the inlet by a suitable pump 3 provided with a discharge line 4 leading to a treating tank 5. The discharge line 4 may terminate near the bottom of the treating tank 5 in a spray head 6. The discharge line 4 may be provided with a valve 7. A level of aqueous caustic soda suspension of preformed lead sulfide is maintained in the treating vessel 5, as indicated at 8. A pressure drop across the sprays 6 provides turbulent contact between the oil and the reagent and the sweetening reaction may be effected merely by this contacting and by the rising of the 25 produced fine droplets of oil through the reagent. Further contacting of the distillate with the reagent may be provided by returning the oil as through the swing pipe 9 and line 10 to the pump 3 and circulating it repeatedly through the reagent in the treating vessel 5, the valve 2 being closed and the valves 1 and 11 being open. Still 30 more vigorous and efficient agitation of the distillate with the reagent may be provided by circulating a stream of the reagent through the pump 3 as through lines 12 and 13, the valve 14 being closed and valves 15 and 16 being open to a 35 point giving the desired flow.

The valve 2, during this recirculation, may be 40 partially open so that the stream leaving the pump 3 by the line 4 may suitably carry 10%, 55 20%, 30% or 40% by volume of recirculated reagent, the remainder being oil undergoing treatment. In treating cracked distillates extremely high in mercaptan content, the amount of reagent 50 recirculated in this manner may constitute 60% of the stream. The contacting in the pump 3 or in the treating vessel 5 should not be severe enough to cause the formation of difficultly 60 broken emulsions of oil and reagent and the agitation in the pump and across the sprays may be governed accordingly. The contact of gasoline with reagent is continued in this manner until the 65 contents of the treating vessel 5 or the gasoline at the discharge of the pump 3, does not react to the doctor test. The circulating pump 3 may be 70 then shut down and the contents of the treating vessel 5 allowed to settle. The treated oil may then be removed as through the swing pipe 9, line 75 10, pump 3, line 4 and discharge line 17, valves 11

and 18 being opened and valves 1, 2 and 15 being closed.

Upon the withdrawal of the treated oil, the system is ready to receive a fresh charge of sour oil.

As noted above, distillates containing relatively 5 small amounts of mercaptans, are sweetened merely by agitating them with a suspension of lead sulfide, but oils containing relatively large amounts of mercaptans (more than about 0.03% mercaptan sulfur) require in addition to this 10 treatment, the presence of a small amount of extraneous air or oxygen during the contacting with the reagent. Such air or oxygen may be supplied at any convenient point in the treating or contacting system. It has been found that such air 15 or oxygen may be most suitably added at the suction side of the charging or mixing pump 3, as, for example, through line 19 provided with a valve 20. In the event that the addition of air at this point causes cavitation of the pump, the line 19 may be 20 placed at the discharge rather than the suction side of the pump.

Air should not be used during the sweetening reaction unless it is found to be necessary and in any case, the addition of air or oxygen should be 25 carefully controlled since any excess air develops the soluble plumbite ion in the reagent. The removal of dissolved lead from the reagent may be effected by the addition of carefully controlled amounts of sodium sulfide to the reagent, or by 30 bubbling a gas containing hydrogen sulfide through the reagent in controlled amounts. This removal of soluble lead may be done between the periods of discontinuous contacting of the reagent with oil or sodium sulfide or other soluble sulfide, 35 or hydrogen sulfide containing gas may be added to the reagent while it is being agitated with the oil.

For example, it may be introduced to the reagent in the treating vessel itself or it may be 40 added to the suction of the charging and mixing pump 3 through the line 21 controlled by the valve 22.

The apparatus disclosed in Fig. 1 is primarily 45 adapted for batch operation and includes means for introducing oil to be treated and contacting it with a reagent, means for circulating any desired proportions of oil and/or reagent through the treating vessel, and means for maintaining the reagent in efficient condition by permitting the 50 introduction of corrective chemicals. A closed system is here employed so that losses are reduced to a minimum.

In Fig. 2, an arrangement of elements particularly adapted for continuous operation is 55 disclosed. A body of the reagent is carried in the treater 25 as indicated by the level line 26. A doctor positive distillate to be treated is continuously admitted by line 27, provided with a valve 28, into the suction line 29 of a pump 30 adapted to discharge by line 31 into one or more spray lines 32 and 32' positioned near the bottom of the treater 25. The discharge line 31 is shown provided with two spray heads so as to afford adequate pressure 60 drop across the sprays at widely differing treating 65 rates.

A discharge line 33 leads from near the top of the treater 25 to a line 34 provided with a valve 35, the line 34 discharging into a settling tank 36. 70 The line 33 may also connect with a line 37, having a valve 38 therein, and a branch 39 communicating with the suction side of the pump 30. The line 39 may be provided with a valve 49.

The lower or bottom portion of the settling 75

5 tank 36 is provided with a discharge line 41 having a valve 42 therein, the line 41 being connected by line 43 having a valve 44 therein, with the bottom of the treating tank 25. The line 41 may also 10 connect with the suction line 29 of the pump 30 as, for example, by communicating with the branch line 39.

15 The top of the settling tank 36 is provided with a discharge line 45 leading to a suitable means 10 adapted to separate solids from liquid as, for example, a filter 46. The line 45 may be provided with a valve 47 and a branch line 48 having a valve 49 therein, said branch line 48 being adapted to by-pass the filter 46 and to place the line 45 in 15 communication with the line 31.

20 In actual operation, the distillate to be treated is continuously admitted through line 27 to the suction line 29 of the pump 30 and discharged by said pump into the spray heads 32 and 32' 25 in the bottom of the treater 25. It is to be understood that a suitable body of reagent is maintained in the treater. A desired proportion of the reagent may be continuously withdrawn from the treater and recirculated as by lines 43, 30 41, and 39, valve 44 being opened the desired amount so as to permit a desired proportion of the reagent from the treater 25 to be continuously withdrawn and recirculated by the pump 30. The treated distillate, together with some 35 reagent, is continuously discharged from the top of the treater 25 by line 33. If valve 33' is closed, then the treated distillate, together with the proportion of the reagent, will pass into line 34 (valve 35 being open) into the settling tank 36 wherein a separation between the distillate and the aqueous caustic soda solution containing lead sulfide in 40 suspension, is effected. The reagent settles to the bottom of the settler 36 and may be continuously withdrawn therefrom by line 41, the valve 42 being open. This settled reagent is thus discharged by lines 41 and 39 into the suction line 29 of the pump 30.

45 The treated distillate is discharged from the top of the settling tank 36 as by line 45, and may be eliminated from the system by lines 48 and 37, valves 49 and 38 being open and valve 40 being closed. A separation between the reagent and the distillate being treated occurs in the treating tank 25 and the treated gasoline can 50 be discharged from the top of the treating tank 25 by line 33 into line 37 and removed from the system through the valve 38. Generally, however, when a large amount of recirculation is 55 being employed and when the rate of treating is high, it is desirable to employ the auxiliary settling tank 36 as described hereinabove. Furthermore, when distillates high in mercaptan sulfur are being treated and it is necessary to introduce air or oxygen into the treater as, for example, 60 by the valved line 50, then it is desirable to employ the auxiliary settling tank.

65 When air is added, its admission should be carefully controlled so that no more is added than is absolutely necessary to effect the sweetening reaction. It is difficult to avoid the formation of soluble lead compounds, however, and as has been noted hereinabove, the presence of plumbite or other soluble lead compounds in the reagent leads to deterioration in the color of the treated oil 70 and a reduction in the rate of sweetening. To avoid the gradual accumulation of soluble lead compounds, it is convenient to add, either intermittently or continuously, small and controlled amounts of sodium or other water soluble sulfide, 75 in order to precipitate the soluble lead as lead

sulfide. This may be conveniently done in continuous operation at the suction side of the pump 30, as through the valved line 51. The reagent should be sampled at various points in the system, as from the bottom of the treater 25, and 10 tested periodically for the presence of soluble sulfides or soluble lead compounds in order to make certain that the additions of corrective agents are merely sufficient to maintain the reagent in substantially balanced condition. The 15 addition of soluble sulfides or soluble lead salts, when and as required, may also be made directly to the body of the reagent in the treating tank 25 as, for example, by the valved line 52.

20 As has been mentioned hereinabove, the lead sulfide reagent used in the process of this invention, exhibits an improved sweetening reaction when some part, at least, of the lead sulfide has become oil-wetted. When a large proportion of the lead sulfide in the reagent is oil-wetted, there 25 is a tendency for some of the lead sulfide to be carried over by the treated distillate. For example, some of the distillate being discharged by line 45 from the settling tank 36, may contain oil-wetted lead sulfide in suspension. In order 30 to prevent the loss of this lead sulfide, it may be desirable to pass the distillate passed from the settler 36 through a suitable means for removing solids therefrom as, for example, a filter press 45. When it is found that the distillate being 35 discharged from the settler 36 contains lead sulfide in suspension, valve 49 may be closed, valve 47 opened, and the distillate passed through the filter, clarifier, thickener, settling tank or other suitable means 46, before being discharged by 40 line 31.

45 The apparatus of the character illustrated in Fig. 2 has satisfactorily and continuously treated California cracked gasoline containing an average of 0.02 mercaptan sulfur without the necessity of the addition of any air whatever to the 45 treating system. In this particular example, the vertical treating vessel 25 was 10 feet in diameter and 30 feet high, agitation being effected both in the treating pump 30 and by the sprays 32 45 and 32' at a treating rate of 500 barrels of 50 gallons each of gasoline per hour. In another example of the process, one volume of reagent has been repeatedly used in the treatment of more than 2,000 volumes of sour gasoline containing 50 about 0.02 mercaptan sulfur without the addition of air or oxygen.

55 This continued reuse was accomplished without loss of lead and without the necessity of adding appreciable quantities of caustic soda over that mechanically lost from the system. When the caustic soda solution has been diluted to materially below 20° Bé. by continued use and the addition of sodium sulfide solution, it is desirable to remove a portion of the aqueous 60 liquor from the solids and to replace it with fresh concentrated caustic soda solution, such as a 30° Bé. caustic. This procedure increases the activity of the reagent and promotes operation.

65 It will thus be seen that a simple and effective method of rendering oils negative to the doctor test, has been disclosed. As repeatedly emphasized hereinabove, the reagent should under no circumstances contain more than traces of soluble lead compounds or of soluble sulfides. If the 70 soluble lead compounds appear in the reagent, they should be precipitated by the addition of carefully regulated amounts of hydrogen sulfide or any soluble sulfide. In case soluble sulfide appears in the reagent, this should be removed 75

5 by the addition of carefully regulated amounts of a soluble lead salt. Sour distillates containing large quantities of dissolved hydrogen sulfide may be preliminarily treated before the sweetening treatment for the removal of the dissolved hydrogen sulfide, as the constant addition of this dissolved gas to the reagent would cause the gradual accumulation of soluble sulfides and the presence of soluble sulfides causes a retardation 10 and finally a cessation of the sweetening reaction.

15 Complete sulfide removal is not necessary, however, it is desirable only that the H₂S content of the sour distillate entering the treating system be no greater than that necessary to reprecipitate the soluble lead compounds which are formed in the reagent during treatment.

20 The following is a typical example illustrating the necessity for maintaining a balanced reagent. A typical mercaptan containing California cracked gasoline was contacted with 8% of a suspension of lead sulfide in 8° Bé. gravity caustic soda solution in the presence of an excess of air. After 20 minutes agitation, the gasoline was 25 negative to the doctor test and the color on the Saybolt chromometer scale was +29. After settling and withdrawing the gasoline, a fresh portion of gasoline was sweetened with the original suspension. After 35 minutes of agitation, 30 the color of the finished gasoline was only +22. The third reuse of this suspension required 85 minutes of contacting in order to produce a doctor negative gasoline but the color of the gasoline had dropped to +16.

35 An exact duplicate of the original reagent was then used for a second series of treatments and the procedure followed was identical except that a lesser quantity of air was present during treatment and after sweetening each portion of gasoline, sodium sulfide solution was added in quantities just sufficient to precipitate the soluble lead compounds formed in the reagent during the previous treating operation. It was found that the second and third portions of gasoline were 40 completely sweetened after but a 5 minute agitation and the colors of the finished gasolines were +30 and +29 respectively. In other words, the time of treatment required when the process was carried out in accordance with this invention was 45 14% and 5% respectively of the time required ordinarily in treating the gasoline. The additional advantage was the improved color of the finished product.

50 Although certain specific concentrations, temperatures, times, conditions and operations have been described in detail, it is to be understood that such conditions, times and ingredients are merely illustrative of the process and are not to be understood as limiting. Numerous changes 55 and modifications can be made as will become apparent to those skilled in the art and all such changes and modifications as come within the scope of the appended claims are embraced thereby.

60 We claim:

65 1. In a process of refining petroleum distillates, the steps of contacting a distillate with an aqueous caustic treating solution containing lead sulfide in suspension in a mixing zone, without 70 the addition of oxygen-containing gas thereto, said caustic treating solution being substantially free from dissolved lead compounds and added free sulfur, maintaining said treating solution substantially free from dissolved lead compounds 75 by the regulated addition thereto of an agent

adapted to precipitate said lead compounds from solution, forcing the mixture of distillate and treating solution into a treating and settling zone, continuously withdrawing a portion of the treating solution from the treating and settling zone, recirculating said withdrawn treating solution through said mixing zone and back into said treating and settling zone, and continuously withdrawing a portion of the treated distillate from the treating and settling zone and from the system.

2. In a process of refining petroleum distillates, the steps of contacting a distillate with an aqueous caustic treating solution containing lead sulfide in suspension in a mixing zone, forcing the mixture of distillate and treating solution into a treating and settling zone, continuously withdrawing a portion of the treating solution from the treating and settling zone, recirculating said withdrawn treating solution through said mixing zone and back into said treating and settling zone, continuously withdrawing a portion of the treated distillate from the treating and settling zone and from the system, and maintaining said aqueous caustic treating solution substantially free from dissolved lead compounds by adding water-soluble sulfides thereto during said recirculation in quantities sufficient to combine with dissolved lead compounds which may be formed during contacting to form lead sulfide.

3. In a process of refining petroleum distillates, the steps of contacting a distillate with an aqueous caustic treating solution containing from about 0.1 to 2.0 pounds of lead sulfide per gallon in suspension in a mixing zone without the addition of oxygen-containing gas, said treating solution being substantially free from water-soluble sulfides, dissolved lead compounds and added free sulphur; maintaining said treating solution substantially free from dissolved lead compounds which may be formed during said contacting by adding quantities of a water-soluble sulfide to said solution to precipitate dissolved lead compounds in the form of lead sulfide, regulating said addition in accordance with the quantity of soluble lead compounds formed in said treating solution; maintaining said treating solution substantially free from water-soluble sulfides which may be formed during said contacting by adding quantities of soluble lead compounds to said solution, regulating said addition in accordance with the quantity of water-soluble sulfides formed in said treating solution; forcing the mixture of distillate and treating solution into a treating and settling zone, continuously withdrawing a portion of the treating solution from the treating and settling zone, recirculating said withdrawn treating solution through said mixing zone and back into said treating and settling zone, and continuously withdrawing a portion of the treated distillate from the treating and settling zone and from the system.

4. In a process of refining petroleum distillates, the steps of contacting a distillate having less than about 0.02%-0.03% mercaptan sulfur with an aqueous caustic treating solution containing from about 0.1 to 2.0 pounds of lead sulfide per gallon in suspension in a mixing zone 70 without the addition of oxygen-containing gas, forcing the mixture of distillate and treating solution into a treating and settling zone, continuously withdrawing a portion of the treating solution from the treating and settling zone, re-

- circulating said withdrawn treating solution through said mixing zone and back into said treating and settling zone, continuously withdrawing a portion of the treated distillate from the treating and settling zone and from the system, and maintaining said aqueous treating solution substantially free from dissolved lead compounds by adding water-soluble sulfides in quantities sufficient to convert all dissolved lead compounds which may be formed during the contacting into lead sulfides.
5. In a process of sweetening petroleum distillates, the steps of forming a suspension of lead sulfide in an aqueous caustic solution of between 8° and 30° Bé., agitating the treating solution with a purified petroleum oil to wet the lead sulfide with oil, separating the aqueous caustic solution and oil-wetted lead sulfide from the purified petroleum oil, then contacting the aqueous 10 caustic solution containing oil-wetted lead sulfide with a sour petroleum distillate, maintaining said caustic solution substantially free from dissolved lead compounds by the regulated addition thereto of an agent adapted to precipitate 15 such lead compounds from solution in the form of a sulfide, agitating the mixture, and finally separating the aqueous caustic solution and lead sulfide suspended therein from the treated distillate.
- 20 6. In a process of refining petroleum distillates, the steps of repeatedly contacting a caustic solution stronger than 8° Bé., containing lead sulfide in suspension, with petroleum distillates, said caustic solution being substantially free 25 from water-soluble sulfides, dissolved lead compounds and added free sulfur, maintaining said solution free from dissolved lead compounds by adding a water-soluble sulfide in minimum quantity required for substantially complete conversion of said soluble lead compounds into lead sulfide, and separating said solution containing lead sulfide in suspension from the treated distillate after said contacting.
- 30 7. A process of refining hydrocarbon distillates 45 containing less than about 0.02% to 0.03% mercaptan sulfur to produce distillates which are negative to the doctor test, comprising contacting such hydrocarbon distillates, without the addition of oxygen-containing gas, with an aqueous alkali solution containing lead sulfide in suspension, and maintaining said solution substantially free from dissolved lead compounds by converting any sodium plumbite which may be formed into lead sulfides by the regulated addition of water soluble sulfides to the solution during said contacting.
- 40 8. A process of refining hydrocarbon distillates 50 containing less than about 0.02% to 0.03% mercaptan sulfur to produce distillates which are negative to the doctor test, comprising contacting such hydrocarbon distillates, without the addition of oxygen-containing gas, with an alkali solution containing from 0.1 to 2.0 pounds of lead sulfide per gallon in suspension, and maintaining said solution substantially free from dissolved lead compounds by converting any sodium plumbite which may be formed into lead sulfides by the regulated addition of water soluble sulfides to the solution during said contacting.
- 55 9. In a process of refining hydrocarbon distillates 60 containing less than about 0.02% to 0.03% mercaptan sulfur to produce distillates which are negative to the doctor test, the steps of contacting such hydrocarbon distillates, without the addition of oxygen-containing gas, with an alkali solution containing from 0.1 to 2.0 pounds of lead sulfide per gallon in suspension, and maintaining said solution substantially free from dissolved lead compounds by converting any sodium plumbite which may be formed into lead sulfides by the regulated addition of water soluble sulfides to the solution during said contacting.
- 65 10. 9. In a process of refining hydrocarbon distillates 70 containing less than about 0.02% to 0.03% mercaptan sulfur to produce distillates which are negative to the doctor test, the steps of contacting such hydrocarbon distillates, without the addition of oxygen-containing gas, with

a caustic solution of between 8° and 30° Bé., and containing 0.1 to 2.0 pounds of lead sulfide per gallon in suspension, and maintaining said solution substantially free from dissolved lead compounds by converting any dissolved lead compounds which may be formed into lead sulfides by the regulated addition of water soluble sulfides to the solution.

10. In a process of refining petroleum distillates containing less than about 0.02% to 0.03% mercaptan sulfur, the steps of recirculating a mixture of such petroleum distillate and an aqueous caustic solution containing lead sulfide in suspension, without the addition of oxygen-containing gas, into and out of a treating zone 15 until the distillate is doctor negative, and maintaining said caustic treating solution substantially free from dissolved lead compounds by the regulated addition of water soluble sulfides to such treating solution in quantity sufficient to convert all dissolved lead compounds which may be formed during such recirculation into lead sulfide.

11. In a process of refining petroleum distillates containing more than about 0.02% to 0.03% mercaptan sulfur to produce distillates which are negative to the doctor test, the steps of recirculating a mixture of such petroleum distillate and an aqueous caustic solution containing lead sulfide in suspension into and out of a treating 30 zone until the distillate is doctor negative, introducing not more than about 0.02 to 0.03 cubic feet of air per gallon of distillate during such recirculation, and maintaining said caustic treating solution substantially free from dissolved lead 35 compounds by introducing regulated quantities of water soluble sulfides into the treating solution in quantity sufficient to convert all sodium plumbite which may be formed during such recirculation into lead sulfide.

12. In a process of treating hydrocarbon distillates containing more than 0.02% to 0.03% of mercaptan sulfur, the steps of contacting such distillate with an alkali solution containing lead sulfide in suspension and free from dissolved lead compounds, introducing not more than about 0.02 to 0.03 cubic feet of air per gallon of distillate during said contacting, and maintaining said solution free from dissolved lead compounds by adding a water soluble sulfide to the solution in regulated quantities sufficient to keep all sodium plumbite which may be formed, in the form of lead sulfide.

13. A process of refining hydrocarbon distillates containing less than about 0.03% mercaptan sulfur to produce distillates which are negative to the doctor test, consisting of contacting hydrocarbon distillates containing less than about 0.03% mercaptan sulfur with a caustic solution of between 8° and 30° Bé., said solution containing lead sulfide in suspension and being substantially free from water-soluble sulfides and dissolved lead compounds; maintaining said solution substantially free from dissolved lead compounds which may be formed during said contacting by adding quantities of a water-soluble sulfide to said solution to precipitate dissolved lead compounds in the form of lead sulfide, regulating said addition in accordance with the quantity of soluble lead compounds existing in said solution; and finally separating the caustic solution from the treated distillate.

14. In a process of sweetening petroleum distillates, the steps of repeatedly contacting an alkali solution containing lead sulfide in suspension with hydrocarbon distillates, adding a water-

soluble sulfide to the solution, during said contacting, in quantity sufficient to precipitate dissolved lead compounds in the form of lead sulfide, regulating the quantity of water-soluble sulfide thus added in accordance with the quantity of dissolved lead compounds formed during said contacting, whereby said alkali solution is maintained substantially free from elemental sulfur and dissolved lead compounds, and then separating said alkali solution from the petroleum distillate after such contacting.

15. In a process of refining petroleum distillates, the steps of: repeatedly contacting an alkali solution containing lead sulfide in suspension with petroleum distillate, said solution being substantially free from water-soluble sulfides and dissolved lead compounds; maintaining said solution free from water-soluble sulfides, during said contacting, by adding a soluble lead compound thereto, during said contacting, in quantity sufficient to combine with water-soluble sulfides formed during treatment of the distillate, to form lead sulfide therefrom; and separating the alkali treating solution from the petroleum distillates after such contacting.

16. In a process of refining petroleum distillates, the steps of: recirculating a mixture of petroleum distillate and an aqueous caustic solution containing from about 0.1 to 2.0 pounds of lead sulfide per gallon in suspension, into and out of a treating zone until the distillate is doctor negative, maintaining said caustic treating solution substantially free from dissolved lead compounds which may be formed during such recirculation by introducing into the circulating solution water-soluble sulfides in quantity sufficient to convert all such dissolved lead compounds into lead sulfides; and separating the treated distillates from the treating solution.

40 17. In a process of sweetening petroleum distillates to produce oils which are negative to the doctor test, the steps of contacting a petroleum distillate containing mercaptans with an alkali treating solution containing lead sulfide in suspension, said solution being substantially free

from dissolved lead compounds, and maintaining said solution substantially free from dissolved lead compounds during such contacting by the regulated addition thereto of a suitable chemical agent adapted to precipitate dissolved lead compounds from said treating solution.

18. In a process of sweetening petroleum distillates to produce oils which are negative to the doctor test, the steps of: contacting a petroleum distillate containing mercaptans with an alkali 10 treating solution containing lead sulfide in suspension, said solution being substantially free from dissolved lead compounds and water-soluble sulfides; maintaining said treating solution substantially free from dissolved lead compounds 15 which may be formed during said contacting by adding quantities of a water-soluble sulfide to said solution to precipitate dissolved lead compounds in the form of lead sulfide; regulating said addition in accordance with the quantity of soluble lead compounds formed; maintaining said treating solution substantially free from water-soluble sulfides which may be present therein by adding quantities of water-soluble lead compounds to said solution, and regulating said addition 20 of water-soluble lead compounds in accordance with the quantity of water-soluble sulfides present in said solution.

19. In a process of sweetening petroleum distillates to produce oils which are negative to the doctor test, the steps of contacting a petroleum distillate containing mercaptans with an alkali 30 treating solution containing lead sulfide in suspension, said contacting being performed in the 35 substantial absence of free sulfur, said solution being substantially free from dissolved lead compounds, and maintaining said solution substantially free from dissolved lead compounds during such contacting by the regulated addition 40 thereto of a suitable chemical agent adapted to precipitate dissolved lead compounds from said treating solution.
